CLAIM

The ornamental design for a medical port, as shown and described.

DESCRIPTION

FIG. 1 is a rear, right, top perspective view of a medical port, illustrating one embodiment of our new design;

FIG. 2 is a rear elevation view thereof;

FIG. 3 is a front elevation view thereof;

FIG. 4 is a right elevation view thereof;

FIG. 5 is a top plan view thereof; and,

FIG. 6 is a bottom plan view thereof.

The broken lines are included for the purpose of illustrating portions of the article that form no part of the claimed design. The broken lines that define the bounds of the claimed design form no part thereof.

1 Claim, 5 Drawing Sheets(56)
